FREQUENCY MODULATION

Harry Tunick, Rye, N. Y., assignor to Radio Corporation of America, a corporation of Delaware

Application August 29, 1941, Serial No. 408,738

7 Claims. (Cl. 179—171.5)

This is a continuation in part of my copending application Serial No. 310,495, filed December 22, 1939. Figures 1, 2, 2a, 2b, 3 and 4 herein are, respectively, original Figures 1c, 2, 2a, 2b, 4 and 5 of my parent application Serial No. 310,495. This application, furthermore, is a continuation in part of my copending application Serial No. 369,800, filed December 12, 1940, since Figure 5 herein is Figure 10 of my copending application Serial No. 369,800, filed December 12, 1940.

Generally, my present invention relates to angular velocity modulation and more particularly to transmitters for producing and transmitting frequency modulated waves. In this respect, it has been proposed to employ oscillation generators having tuned grid and tuned plate circuits for the production of frequency modulated waves by varying the tuning of, say, the tuned grid circuit in accordance with the modulation. Since the grid circuit tuning is varied and the plate circuit remains fixed in tuning, the variable frequency currents are phase distorted, i. e., shifted in phase in the plate circuit which is, of course, undesirable. One object of my present invention is to provide an improved system for frequency modulated waves which shall be substantially free of this type of distortion, namely, phase distortion. Other objects, advantages and features of my invention will appear as the more detailed description thereof proceeds.

In the drawings, Figure 1 is a wiring diagram of an oscillator having separate tuned input and output circuits and appropriate reactance tube systems for simultaneously varying the tuning of the input and output circuits to thereby produce angular velocity modulated waves substantially free of phase distortion; Figure 2 illustrates another modification of my invention in which, among other things, the plate and grid circuits of a crystal controlled oscillator are simultaneously varied to produce frequency modulation of the generated waves; Figures 2a and 2b are explanatory curves illustrating signal pre-emphasis and de-emphasis at the transmitter and receiver, respectively; Figure 3 illustrates a modification of Figure 2; Figure 4 illustrates a system for producing frequency modulation simultaneously by varying the screen grid and plate voltages of an oscillation generator; and Figure 5 is a modified form of the system shown in Figure 1.

Referring to Figure 1, tubes 26, 28 are provided with a tuned input circuit 20 and a tuned output or plate circuit 34. Grid circuit 20 comprises coil 22 shunted by variable tuning condenser 24 and, similarly, the tuned plate circuit 34 consists

of a coil 36 shunted by a variable condenser 38. Oscillations are generated regeneratively by the cross-connected feedback condensers 30, 32. Output is taken from the by-passing condensers 40, 42 as illustrated. Amplified signals, as explained in my parent application Serial No. 310,495, are fed through transformer 6 and lead 8 to the screen grids 10, 12 of reactance tubes 14, 16. In case video signals are transmitted, radio frequency by-pass condenser 18 should be made smaller so as not to by-pass the highest video frequencies fed through transformer 6. If desired, condenser 18 may be omitted.

The reactance tubes 14, 16 act to change the tuning of the grid circuit 20, comprising coil 22 and condenser 24, an amount proportional to the amplitude of the signal fed through transformer 6 and at a rate or frequency identical to the frequency of the signal fed through transformer 6. As a consequence, the push-pull connected oscillator tubes 26, 28 regeneratively cross coupled by condensers 30, 32, produce frequency modulated high frequency oscillations in the tank or plate circuit 34 comprising inductance coil 36 and condenser 38. The frequency modulated oscillations are fed through condensers 40, 42 to a power amplifier and/or limiter and/or frequency multipliers and eventually to an antenna, as explained in my parent application Serial No. 310,495.

Automatic frequency controlling voltages may be fed through lead 1b to the suppressor grids 144, 146 of reactance tubes 14, 16 and also, as illustrated, to the suppressor grids of reactance tubes R16, R14. Similarly, the signal is fed from the secondary of transformer 6 to the screen grids R10, R12 of reactance tubes R14, R16. Over-modulation control voltages derived as explained in my parent case Serial No. 310,495 may be inserted through resistor 234.

Reactive voltage substantially in quadrature with that existing at the upper terminal of tuned grid circuit 20 is impressed upon the grid 156 of reactance tube 14 through the action of condenser 148 and resistor 152. Similarly, a quadrature voltage with respect to the voltage at the lower terminal of circuit 20 is impressed on grid 158 through the action of condenser 150 and resistor 154. The plates of the reactance tubes 14, 16 are fed with suitable plate voltage through chokes 162, 164 which are appropriately bypassed by by-passing condensers 166, 168. Condensers 170 and 172 are large coupling condensers.

As already explained, a second pair of react-

ance tubes R14, R16 are connected to the plate circuit 34. The suppressor grids R144 and R146 of the plate circuit reactance tubes R14, R16 are connected in parallel and to the suppressor grids 144, 146 of reactance tubes 14 and 16. Similarly, screen grids R10, R12 are connected in parallel and to the screen grids 10, 12 of the grid circuit reactance tubes 14, 16. Phase displaced voltages are taken from the plate circuit 34 and fed to the control grids R156 and R158 by means of condensers R148, R150 and resistors R152, R154.

In view of the foregoing description, it will be observed that the signal input not only varies the tuning of the grid or input circuit 20, but it also simultaneously changes the tuning of the circuit 34. In this way, phase distortion of the modulated currents is avoided. That is to say, if, for example, circuit 34 were not simultaneously tuned to the grid circuit 20, then as the circuit 20 is altered in frequency, the circuit 34 would present undesired reactance to the changed frequency of oscillation and, hence, would introduce phase shifts which are undesired. By simultaneously varying both the grid and plate circuits this defect is circumvented.

In the transmitter of Figure 2, microphone 300 feeds an audio frequency amplifier 302 whose characteristic is as shown in Figure 2a. That is, amplifier 302 should have a flat characteristic along the range A to B of about 10 to 500 or 10 to 1000 cycles. From points B to C the characteristic should rise preferably linearly. B to C represents the remainder of the audio frequency range which may be as desired from 500 or 1000 to 5000, 7500 or 10,000 or more cycles. When such an amplifier is used at the transmitter, the frequency modulation audio frequency amplifier at the receiver should have a complementary characteristic, namely, flat along the frequency range from A to B and then drop off from the frequency range B to C, as shown in Figure 2b.

The output of audio frequency amplifier 302 is fed through transformer 304 and additional transformers 306, 308 to the grids of reactance tubes 310, 312. Audio frequency by-passing condensers 314, 316 are provided as are also radio frequency chokes 318, 320. Depending upon the adjustments of reactance tubes 310, 312 the crystal 322 is effectively shunted by variable capacity or inductance represented by tube 310 and the plate circuit of the crystal controlled oscillation generator tube 324 is also shunted by a variable inductor or capacity represented by reactance tube 312. Both tubes 310, 312 should be adjusted so as to add similar reactances, namely, capacitive or inductive, to the grid and plate circuits of crystal controlled generator 324. If desired, of course, the crystal may be replaced by a tuned circuit or a quarter wave resonant line. The audio frequency voltages applied to the reactance tubes 310, 312 may be adjusted by virtue of taps 330, 332 on the potentiometer shunting the secondary of transformer 304. The output of the oscillation generator may be fed through a limiter and/or power amplifier and/or frequency multiplier 334 whose output is radiated by the antenna 336.

Over-modulation pickup antennae or coils 338, 340 are provided, antenna 338 feeding into a circuit 342 tuned to or slightly beyond one extreme frequency of the channel assigned to the transmitter of Figure 2. Similarly, tuned circuit 342 is tuned to or slightly beyond the other extreme frequency of the channel assigned to the transmitter. Circuit 340 energizes amplifier 344, in 70

turn connected to rectifier 346. When the swing exceeds the channel allotted to the transmitter, an indication is produced in indicator 348 and to automatically prevent this condition from persisting, an automatic volume control lead 350 is provided. Lead 350 may be connected to one of the audio stages of amplifier 302 to cut down its gain when output is produced in rectifier 346. Similarly, when the transmitter goes beyond its extreme allotted frequency in the other direction, rectifier 352 becomes active to produce an indication in the bell or lamp indicator 354 and also inject a gain reducing voltage in the automatic volume controlling lead 356 leading to the same 15 or another amplifier stage in audio frequency amplifier 302. If desired, the system may be operated without the automatic volume controlling feature, in which case switch 360 and/or switch 362 may be opened.

20 In the transmitter of Figure 3, reactance tubes 800, 802 are made more conductive by the action of transformer 804 associated with the cathodes of reactance tubes 800, 802. Transformer 804 is energized by signal amplifier 806 in turn connected, if desired, to a microphone 810. Condenser 812 and resistor 814 are adjusted so as to energize the grid 816 with a relatively leading voltage. Condenser 818, coil 816 and resistance 820 are adjusted so as to impress a relatively lagging voltage with respect to the voltage at point 822 upon the grid 824 of tube 802. The cathodes of the reactance tubes are connected to a source of potential 830 such that both tubes draw a mean current in the absence of signal from amplifier 806. The apparatus within box 840 is identical to that within the dotted rectangle 842. By the action of switch 844 either the crystal 846, parallel tuned circuit 848 or resonant line 850 is connected in the grid circuit of the high frequency oscillation generator 852. The output of the generator 852 is fed through power amplifier and/or limiter and/or frequency multiplier to antenna 856.

45 Obviously, both reactance tubes 800, 802 may be adjusted so that they both draw leading currents or both drawing lagging currents. Preferably, coil 816 is omitted and condensers 812, 818 are made identical in size so that both reactance tubes 800, 802 act alike.

50 In the transmitter of Figure 4, the oscillator tube 900 may have either crystal 902 connected between the plate 904 and grid 906 or, as shown, the series tuned circuit 908 is connected by means of switch 910 between the plate 904 and grid 906. The screen grid 920 is supplied with voltage through radio frequency choke 922 and by-pass condenser 924. The plate 904 is supplied with plus voltage through choke 930 bypassed by by-passing condenser 932. Transformers 934 and 936 insert alternating signal voltages in the plate and screen voltage leads. These signal voltages are derived from potentiometer 940 connected to the secondary of transformer 942 whose primary is connected across the plates of push-pull amplifier 944 energized from audio or signaling amplifier 946. Since like voltage changes applied to the screen 920 and plate 904 produce opposite effects on the frequency of oscillation of tube 900 transformers 936 and 934 are so polarized as to oppositely swing the screen 920 and plate 904 in voltage in accordance with signal voltages derived from amplifier 946. The output circuit 950 of the oscillator 900 is fed to the limiter 952 which may

be a power amplifier and/or frequency multiplier and in turn 952 energizes the antenna 954.

In the transmitter of Figure 5, tubes 2', 4' are provided with tunable high frequency input and output circuits 6' and 8' respectively. Feed-back causing high frequency oscillation generation is accomplished by means of feed-back condensers 10, 12.

Tubes 14' and 16' are connected symmetrically and to opposite sides of the tuned circuit 8' by means of condensers 18' and 20'. It will be appreciated, therefore, as the tubes 14' and 16', which have their grids connected in parallel by means of lead 22', are made more conductive, more and more capacity is effectively connected in shunt to circuit 8', thereby lowering the frequency of oscillation of the oscillation generating tubes 2', 4'.

Tubes 30', 32', which have their grids connected in parallel by lead 34, are connected to opposite sides of the plate tuned circuit 8' through inductors 36', 38'. Hence, as the tubes 30', 32' are made more and more conductive, more and more inductance is effectively connected in shunt with the coil of the tuned circuit 8' and, hence, this acts to reduce the total inductance in circuit and, hence, raise the frequency of oscillation.

For frequency modulating the push-pull oscillation generator 2', 4' the leads 22', 34' are connected as shown to opposite sides of the secondary of transformer 40'. The primary of the latter is fed with amplified voice or tone currents from amplifier 42 in turn supplied by microphone 44'. By making the amplifier 42 have a rising characteristic for the modulating frequencies fed to its input side, the resulting output of the system taken from leads 46, 48 will be phase modulated.

The tunable grid circuit of the transmitter of Figure 5 may be similarly varied in frequency by means of tubes 50', 52' connected to opposite sides of the tuned circuit 6' through condensers 54' and 56' and by means of tubes 60', 62' also connected to opposite sides of the grid circuit 6' through inductors or coils 64', 66'. Large by-passing condensers 68' and 70' are provided to prevent the application of plate voltage applied to the plates of 60' and 62' from the grids of the oscillation generator tubes 2', 4'. The grids of tubes 50' and 52' are connected in parallel and to one side of the secondary of modulation frequency transformer 80'. Similarly, the grids of tubes 60' and 62' are connected in parallel and to the other side of the secondary of transformer 80'. The primary of transformer 80' is connected in shunt to the output of amplifier 42' or in parallel to the primary of transformer 40'. Obviously, transformer 40' may be eliminated and the frequency modulation produced by changing only the tuning of the grid circuit or, as shown, both grid and plate circuits may be simultaneously varied.

Having thus described my invention, what I claim is:

1. An oscillation generator having a resonant input circuit and a separate resonant output circuit independent of said resonant input circuit, a

source of modulating waves, and means for simultaneously varying the resonance of said input circuit and said output circuit in response to waves from said source to thereby vary the frequency of oscillations generated.

2. In combination, a push-pull connected vacuum tube oscillation generator having a parallel tuned plate circuit and a parallel tuned grid circuit, a pair of reactance tubes symmetrically connected to the grid circuit, another pair of reactance tubes symmetrically connected to said plate circuit, and means for simultaneously varying the conductivities of all of said reactance tubes in order to thereby simultaneously vary the frequency of oscillations generated by said generator.

3. Apparatus as claimed in the preceding claim, characterized by the provision of means connected to the tuned grid circuit for supplying the grids of the reactance tubes symmetrically connected to the grid circuit with phase displaced voltages relative to the voltages across the grid circuit, and being further characterized by the fact that means are provided for supplying the grids of the reactance tubes connected to the plate circuit with phase displaced voltages displaced in phase with respect to and derived from voltages across said plate circuit.

4. In combination, an oscillation generator having a tuned input circuit and a tuned output circuit, a pair of reactance tubes symmetrically connected to said tuned input circuit, a second pair of reactance tubes symmetrically connected to said tuned output circuit, and means for simultaneously varying the conductivity of all of said reactance tubes and thereby varying the frequency of oscillations generated by said generator.

5. In combination, a vacuum tube oscillation generator having a resonant grid circuit and having a separate resonant plate circuit, an electron discharge device connected to said grid circuit through a reactance, a second electron discharge device connected to said plate circuit through another reactance, and means for simultaneously varying the conductivity of said tubes with control voltages to simultaneously change the tuning of said grid and plate circuits.

6. In combination, a push-pull vacuum tube oscillation generator having a resonant grid circuit and a resonant plate circuit, a pair of electron discharge devices connected to said grid circuit through reactors, another pair of electron discharge devices connected to said tuned plate circuit through another pair of reactors, and means for varying the conductivities of said pairs of devices with control voltages so as to simultaneously vary the tunings of said grid and plate circuits.

7. In combination, a high frequency circuit, a pair of electron discharge devices connected to said circuit through capacitive reactances, a second pair of electron discharge devices connected to said circuit through inductive reactances, and a circuit for oppositely varying the conductivities of said pairs of devices to thereby alter the tuning of said first-mentioned circuit.

HARRY TUNICK.
